UNITED STATES PATENT OFFICE.

HARRY P. TAYLOR, OF LOS ANGELES, CALIFORNIA.

MILL.

1,414,602.

Specification of Letters Patent. Patented May 2, 1922.

Application filed June 29, 1920. Serial No. 392,807.

To all whom it may concern:

Be it known that I, HARRY P. TAYLOR, a citizen of the United States, and a resident of the city of Los Angeles, in the county of Los Angeles and State of California, have invented certain new and useful Improvements in Mills, of which the following is a specification.

My invention relates to mills of the type wherein a drum is employed and wherein material to be reduced is confined in the drum with reducing bodies such as bars, rods, rollers, balls or the like, the drum then being rotated or otherwise agitated to cause the material to be reduced to the desired degree of fineness. The drum is provided with a discharge end through which the material after being reduced is discharged automatically.

The invention is primarily directed to the discharge end of the mill and in the present construction I have provided means whereby the material may be freely discharged from the mill after being reduced, the size of the discharge opening or openings being adjustable and means other than the discharge opening being provided whereby access may be had to the interior of the drum while the mill is in operation.

A mill of this type possesses many advantages and by my construction the reducing bodies such as rods for example may be removed or replaced without necessitating stopping of the mill.

I have shown in the accompanying drawings several embodiments of my invention, it being understood, of course, that the drawings are merely illustrative and not definitive.

Fig. 1 being a part sectional elevation of a mill provided with my invention;

Fig. 2 is an end view of the structure of Fig. 1 looking at the discharge end;

Fig. 3 is a modification of the apparatus of Figs. 1 and 2; and

Fig. 4 is an end view of the mill of Fig. 3 looking at the discharge end.

Referring now to the embodiment of my invention as illustrated in Figs. 1 and 2, 50 1 designates a rotatable drum mounted for

rotation about a fixed axis on rollers 2 and in a trunnion bearing 3. The trunnion bearing in the present instance is at the feed end of the mill and the material is fed to the mill through an open trunnion 4.

The drum is provided at its discharge end 5 with an annular inwardly or transversely extending flange 6 secured to the drum in any suitable manner. This flange may be inclined if desired, as I have indicated in the drawings and is provided with a continuous discharge opening 7 in its working face, that is to say, its inner side or the face adjacent the reducing compartment 8 of the drum, by which material may be continuously discharged from the mill through the flange. The opposite face of the flange is provided with lugs 9 and discharge openings 10, the latter communicating with the continuous uninterrupted discharge openings 7 already referred to. It will be seen that the openings 7 and 10 in the flange constitute a continuous discharge opening in the flange whereby the material may be discharged from the drum continuously through the flange and that the lugs 9 which I have referred to are merely for the purpose of securing that portion of the flange at one side of the openings 7 and 10 to that portion of the flange at the other side of said openings so that the opposed walls of the openings 7 and 10 may be said to be fixed relatively to each other. It will be apparent that when the material is being discharged from the mill it will be discharged through the flange 6 by way of the openings 7 and 10 and past the lugs 9.

The flange 6 defines a comparatively large central opening 11 in the end of the mill which opening is maintained closed to prevent the discharge of material therethrough from the reducing compartment 8 by a closure member or door 12. This door is supported, as shown in Fig. 2, on a fixed support 13 upon which it is hinged in order that it may be moved into and out of closing position with respect to the opening 11. The door when closed as shown in Fig. 1 is maintained in such position by any suitable locking means such as 14 (see Fig. 2). The door 100

is mounted for rotation in a bearing 15 so as to be freely movable with the drum 1 when the mill is in operation. The end of the drum opposite to the discharge end is 5 provided with a gear 16 in mesh with a small gear 17, the latter being driven through any suitable gear train or otherwise by a motor 18. The drive for this mill is merely 10 illustrative and not definitive as obviously the drum may be rotated in any desired manner.

Mounted on the flange 6 adjacent the discharge openings 10 are plates or slides P, these plates being adjustable to vary the size 15 of the openings 10 to thereby vary the size of the material discharged from the mill as well as to raise or lower the pulp line in the mill. This regulation or adjustment of the discharge openings is entirely independent 20 of the door or closure member 12.

It will be seen from the foregoing that I have provided in this embodiment of my invention a mill wherein the material to be reduced is introduced into the reducing 25 compartment 8 of the drum 1 and is there reduced to the desired degree of fineness by rotating the drum together with the material to be reduced and any of the well-known types of reducing bodies, such as those mentioned above. As the mill rotates the reduced material is automatically discharged therefrom through the flange 6 by way of 30 the discharge opening comprising the openings 7 and 10, it being understood that in normal operation the door 12 is closed as shown in Fig. 1 so that no material is discharged from the mill except through the openings 7 and 10. Should it be desired to 35 observe the interior of the mill while the same is in operation it is merely necessary to swing the door 12 out of closing position with respect to the opening 11 and if desired the reducing bodies may be removed or replaced without necessitating shutting down 40 of the mill.

It will be apparent therefore that in this embodiment of my invention I have provided an inwardly-extending flange at the discharge end of the drum 1 which flange is 45 provided at its face adjacent the crushing compartment 8 with a continuous discharge slot 7 communicating with the slots 10 at the opposite side of the flange whereby material is free to be discharged automatically from the drum through the flange as the same is rotated. It will be apparent also that by adjusting the plates P the pulp line 55 may be raised or lowered and the size of the material discharged from the mill regulated.

60 In the embodiment of my invention illustrated in Figs. 3 and 4 I provide a drum 19 mounted at one end on roller bearings 20, the opposite end of the drum being mounted in the trunnion bearing 21 for example, 65 this end of the drum being provided with a

gear 22 meshing with a small gear 23 driven from any suitable source of power, as an electric motor 24. The drum is lined with suitable liners 25.

At the discharge end of this mill I provide an end liner 26 either in one piece or in sections as desired and extending inwardly so as to form an inwardly extending flange similar to the flange 6 of Fig. 1. This liner is provided at its face adjacent the 75 crushing compartment 27 of the mill with a continuous discharge opening 28 by which material is discharged through the liner, this opening communicating with a discharge opening 29 adjacent the opposite face 80 of the liner. The opening 29 is interrupted at intervals by projections 30 on the liner. The liner proper defines the boundaries of a central opening 31 in the discharge end of the mill which opening is provided with a 85 door 32 similar to the door 12 of Fig. 1. A ring 33 having a peripheral flange 34 is adapted to be secured to the drum 19 in any suitable manner as by bolts 35. This ring at intervals is cut out to form notches 36 90 which are adapted to cooperate with the projections 30 of the liner 26 so that relative rotation of the liner to the ring is effectually prevented. As a means of securing the liner 26 in place I have shown bolts 37 passing through the ring 33 and the liner. This construction therefore provides for discharge of material from the drum automatically through openings provided in the liner 26, these openings being those above referred 95 to and designated 28 and 29.

It will also be seen that the central opening 31 defined by the liner 26 which is normally maintained closed by the door 32 affords means for observing the interior of the 105 mill for the purpose of inspecting the reducing bodies therein or for any other purpose without necessitating closing down of the mill. In this instance I have provided plates P' similar to the plates P of Fig. 1 110 for the purpose of varying the size of the discharge openings and regulating the pulp line as desired.

In each of the constructions illustrated I have shown, for convenience only, the inner 115 face of the flange inclined outwardly to provide a better discharge for the material, it being understood, of course, that if desired the inner face of the flange may be straight up and down.

It will be seen from the foregoing description that by providing the inclined flange or the door with an inclined face at the discharge opening of the mill and by making the discharge opening either in the flange or 125 the door, as the case may be, continuous, on the side adjacent the crushing compartment of the mill danger of the reducing bodies, such as rods, clogging the discharge opening is eliminated inasmuch as the tendency of 130

the reducing bodies is to work away from the discharge end of the mill by reason of the inclined faces mentioned.

It will be seen from the foregoing that I have provided a mill comprising a drum having an annular flange at the discharge end thereof, said flange extending transversely of the drum and being provided with a continuous unobstructed opening in the working face thereof, that is to say, in the face adjacent the reducing compartment of the drum whereby material may be continuously discharged from the mill through said flange. In fact it will be seen that when the mill is in operation there is no interruption in the discharge of the material from the mill inasmuch as the material is at all times free to flow or be discharged from the mill through the flange uninterruptedly and continuously through the openings 7 and 10, the material being divided as it is discharged through the outer face of the flange by the lugs 9 which as I have hereinbefore pointed out, are merely provided for the purpose of securing the two parts of the flange together whereas the flange otherwise would be divided into two pieces.

What I claim as new is:

1. In a mill of the character described, a drum having an annular flange at one end thereof defining the boundaries of a central opening, said flange extending transversely of the drum and being provided with a continuous uninterrupted opening in the working face thereof whereby material is continuously discharged from the mill through the flange.

2. In a mill of the character described, a drum having a discharge end, and an annular flange at said discharge end, the face of said flange adjacent the interior of the mill being provided with a continuous opening, said flange being provided with a series of openings in its opposite face communicating with said continuous opening, said openings constituting discharge openings for the mill whereby material is discharged from the mill through said flange.

3. In a mill of the character described, the combination of a drum, a member at one end thereof defining the boundaries of a central opening at the discharge end of the mill, means for closing said opening when the mill is in operation, the said member at the discharge end of the mill being provided with a continuous uninterrupted opening in the interior face thereof whereby material is discharged from the mill through said member.

4. In a mill of the character described, the combination of a drum having a discharge end, an inwardly-extending member at said discharge end defining the boundaries of a central opening in the discharge end of the mill, a closure member for said opening,

movable relatively to said drum said inwardly-extending member having discharge openings therein, and means for varying the size of said discharge openings.

5. In a mill of the character described, a drum having a discharge end, a member at said discharge end defining the boundaries of a central opening in the discharge end of the mill, a closure for said opening, the face of said member adjacent the interior of the drum being provided with a continuous opening communicating with openings in the opposite face of said member, said openings constituting discharge openings for the mill.

6. In a mill of the character described, a drum having a discharge end, a member at said discharge end defining the boundaries of an opening at the discharge end of the mill, said member being provided with an opening constituting a discharge opening for the mill, and a rotatable plug constituting a closure for the opening first-named, said plug being movable away from said opening to permit access to the interior of the drum while material is being discharged through said discharge opening.

7. In a mill of the character described, a drum having a discharge end, and an inclined inwardly-extending flange rigid with said drum and provided with an opening for permitting the discharge of material from the drum through said flange.

8. In a mill of the character described, a drum having a discharge end, end liners at said discharge end of the mill provided with a continuous discharge opening on their inner faces and a series of openings in the opposite face, said openings jointly constituting discharge openings for the mill, and a ring secured to said liners and to said drum.

9. In a mill of the character described, a drum having a discharge end, a liner at said discharge end provided with an offset portion having an opening to the exterior of the mill, an opening on the opposite face of said liner and communicating with the first-mentioned opening so that discharge openings for the mill are provided, and a ring secured to said drum and having a notch engaging said offset portion of the liner.

10. In a mill of the character described, a drum having a discharge end, a liner at said discharge end provided with a central opening, said liner being provided with an offset portion having an opening communicating with the interior of the mill, a ring to which said liner is secured and having a notch engaging said offset portion of the liner to prevent relative rotation of said liner and ring, said ring being secured to the drum, and a movable closure member for the central opening in the liner, permitting access to be had to the interior of the mill while

material is being discharged through the discharge opening.

11. In a mill of the character described, a drum having a member at the discharge end thereof provided with an adjustable continuous opening for the discharge of material therethrough.

12. In a mill of the character described, a drum having an annular flange at one end thereof, said flange extending transversely of the drum and being provided with an adjustable continuous discharge opening therein.

13. In a mill of the character described, the combination of a drum, a flange at one end thereof defining an opening at the end of the drum, a closure for said opening supported independently of the drum, said flange being provided with an opening for effecting a discharge of material from the drum through said flange, and a connection

wholly exterior of the working face of said flange for connecting the opposed walls of the discharge opening to each other.

14. In a mill of the character described, the combination of a drum, a transversely extending flange at one end of the drum defining the boundaries of an opening at the end of the drum, and a closure for said opening supported independently of the drum, said flange being provided with a discharge opening for effecting a discharge of material through the flange.

15. In a mill of the character described, a drum and a member at the discharge end thereof provided with a discharge slot extending uninterruptedly for a complete turn about the axis of rotation of the drum.

This specification signed this 18th day of June, 1920.

HARRY P. TAYLOR.
